UNITED STATES PATENT OFFICE.

STEPHEN J. CLULEE, OF ATTLEBORO, MASSACHUSETTS.

EYEGLASS CONSTRUCTION.

1,224,361.

Specification of Letters Patent.

Patented May 1, 1917.

Application filed May 3, 1915. Serial No. 25,479.

To all whom it may concern:

Be it known that I, STEPHEN J. CLULEE, a citizen of the United States, and residing at Attleboro, in the county of Bristol and 5 State of Massachusetts, have invented a new and Improved Eyeglass Construction, of which the following specification is a full disclosure.

This invention relates to eyeglass construction. One of the objects thereof is to 10 provide simple, practical and reliable means for securing a supporting member to an eyeglass lens. Another object is to provide means of the above type which may be used 15 quickly and conveniently and at a low cost. Another object is to provide an art of securing together an eyeglass lens and a supporting member.

Other objects will be in part obvious and 20 in part pointed out hereinafter.

The invention accordingly consists in the features of construction, combinations of elements, arrangement of parts, and in the several steps and relation and order of such 25 steps which will be set forth in the following description, and the scope of the application of which will be indicated in the appended claims.

In the accompanying drawing, in which 30 is shown one of various possible embodiments of the mechanical features of this invention, Figure 1 is a side elevation of a lens with a supporting member or clamp mounted thereon. Fig. 2 is a cross-section 35 taken along the line A—A of Fig. 1.

Similar reference characters refer to similar parts throughout both views of the drawing.

Referring now to Fig. 1 of the drawing, 40 there is indicated at 1 an eyeglass lens, and it may here be noted that the term "eyeglass" is used throughout to comprehend spectacles and like devices, as well as glasses mounted upon the nose. Secured to lens 1 45 is a lens clamp comprising a strap portion 2 and side wings or lugs 3. This lens clamp may be secured in any desired manner to the bridge or nose-piece, the securing means not being shown as they form in themselves 50 no part of the present invention.

As best shown in Fig. 2 of the drawing, there is provided in the inner surface of each lug 3 a recess 4 having side walls which are preferably undercut as indicated at 5. 55 These recesses may be of any desired contour, such as that indicated by the dotted

line 6 in Fig. 1 of the drawings. Formed in the base or strap portion 2 is a recess 7, also undercut, and preferably extending for a substantial distance circumferentially of 60 the lens, as indicated at 8 in Fig. 1 of the drawing.

Recesses 4 and 7 are filled with a vitreous substance, such as enamel, which is preferably fused to the contacting surfaces of the 65 lens clamp, the latter term being broadly used to cover any device of this general nature secured to an edge of the lens. There is thus provided throughout a considerable proportion of the interior of the lens clamp 70 a non-metallic and preferably glazed surface which adheres to the metal of the lens clamp with the greatest tenacity. In so far as the broader features of this invention are concerned, this enameling may be applied directly to the inner surface of the lens clamp 75 without forming the recesses 4 and 7, but there are many advantages in the arrangement shown.

The lens clamp thus formed is fitted about 80 the edge portion of the lens 1 at the proper point and securely cemented thereto by a suitable adhesive which may, if desired, be fusible at a low temperature to permit removal of a broken lens.

It being understood that prior to mounting the lens clamp in position the vitreous enamel is fused, as by baking, to the surface of the metal, and inasmuch, further, as a glassy substance of this nature may be cemented to the glass of the lens with far greater tenacity than it is practicable to cement metal to glass, it will be seen that an extremely strong connection may be 90 made. Furthermore, by the use of the several recesses, as shown, there is provided a three-point connection which is rigid and durable to a high degree. Also, a cement is 95 here employed which is specifically adapted and intended to adhere to a glassy surface 100 without having to so modify it and impair it as to adapt it for adhesion to a metallic surface, as when metal is cemented directly to glass. Furthermore, the effect of the 105 expansion and contraction of the metal with varying temperature does not here tend to loosen the attachment of the lens clamp with the lens.

The method of use of the above device has been described in substance, but it may be 110 noted that when the lens is to be secured to the clamp, there is preferably applied to

- the interior of the clamp a thin film of readily fusible cement, the clamp being heated, and the lens is then properly positioned between the side wings of the clamp.
- 5 When the parts cool, there is thus provided a joint in which the fused inserts not only interlock with, but form substantially a part of, the clamp and these as well as the metallic surface of the clamp are cemented in
- 10 place to the engaging surface of the lens with a cement which will securely hold them in position.

It will thus be seen that there is provided a device and an art in which the objects of 15 this invention are achieved and which are well suited to withstand conditions of the hardest practical use.

As various changes might be made in the 20 above construction, and as the above described art might be carried on in a somewhat different manner, it is intended that all matters shown in the accompanying drawing or set forth in the foregoing description shall be interpreted as illustrative 25 and not in a limiting sense.

Having thus revealed this invention, I 30 claim as new and desire to secure the following combinations of elements, or equivalents thereof, by Letters Patent of the

35 United States:

1. In eyeglass construction, in combination, a lens, a lens clamp formed to present a glazed surface for engagement with said lens, and means cementing said glazed surface to said lens.

2. In eyeglass construction, in combination, a lens clamp having a vitreous material fused against its inner surface in position to engage the lens.

3. In eyeglass construction, in combination, a lens, a lens clamp having a refractory non-metallic material fused against its inner surface, and means cementing said non-metallic surface to said lens.

4. In eyeglass construction, in combination, a lens, a lens clamp having a refractory non-metallic material fused against its inner surface, and means cementing said non-metallic surface to said lens, said non-metallic material being positioned on the

inner surface of each side lug and of the strap portion of the clamp.

5. In eyeglass construction, in combination, a lens, a lens clamp having a plurality of recesses in its inner surface, a vitreous material secured within each of said recesses to form inserts therein, the surfaces of said inserts being adapted to fit smoothly and closely the outer surface of an edge portion of said lens, and means cementing said vitreous material to the engaging surfaces of said lens.

6. In eyeglass construction, in combination, a lens, a lens clamp having a plurality of recesses in its inner surface, a vitreous material secured within each of said recesses to form inserts therein, the surfaces of said inserts being adapted to fit smoothly and closely the outer surface of an edge portion of said lens, and means cementing said vitreous material to the engaging surfaces of said lens, said vitreous material being fused to the surfaces of the metallic lens clamp which it engages.

7. The art which comprises fusing a vitreous material against the inner surface of a metallic lens clamp, inserting a lens within said clamp with cement fusible at low temperature between the surface of the lens and the surface of said vitreous material, 80 said cement being heated to a temperature above its fusing point and below the fusing point of said vitreous material, and permitting said cement to cool.

8. The art which comprises applying 85 enamel fusible at high temperature to the inner surface of a lens clamp and fusing it against the same to form smooth exposed surfaces, interposing a cement fusible at low temperature between said enamel and the 90 surface of a lens fitted in said clamp, heating said cement to a relatively low temperature to fuse it, and permitting the parts to cool.

In witness whereof, I hereunto subscribe my name, as attested by the two subscribing 95 witnesses.

STEPHEN J. CLULEE.
